PAGE 2

Fig. 3.

Fig. 4.

Fig. 1 is a front perspective view of a transom drive unit for a boat, showing my new design;

Fig. 2 is a rear perspective view thereof;

Fig. 3 is a front elevation of the unit;

Fig. 4 is a top plan view thereof; and

Fig. 5 is a side elevation thereof.

I claim:

The ornamental design for a transom drive unit for a boat, substantially as shown.
